Primary Examiner—Brian N. Vinson*Attorney, Agent, or Firm*—Henricks, Slavin & Holmes LLP**[57] CLAIM****The ornamental design for a blade disposal apparatus, as shown and described.****DESCRIPTION**

FIG. 1 is a top, front, and right side perspective view of a holder unit for a blade disposal apparatus showing my new design, the broken-line disclosure of a disposal apparatus being for illustrative purposes only and forming no part of the claimed design;

FIG. 2 is an enlarged top, front, and right side perspective view thereof;

FIG. 3 is an enlarged left side elevational view thereof, the undisclosed right side being a mirror image of that shown

FIG. 4 is an enlarged front elevational view thereof;

FIG. 5 is an enlarged rear elevational view thereof;

FIG. 6 is an enlarged top plan view thereof; and,

FIG. 7 is an enlarged bottom plan view thereof.
